UNITED STATES PATENT OFFICE.

HERMANN LEMP, OF LYNN, MASSACHUSETTS, ASSIGNOR TO GENERAL ELECTRIC COMPANY, A CORPORATION OF NEW YORK.

INTERNAL-COMBUSTION ENGINE.

1,093,140.

Specification of Letters Patent. Patented Apr. 14, 1914.

Application filed June 24, 1911. Serial No. 635,118.

To all whom it may concern:

Be it known that I, HERMANN LEMP, a citizen of the United States, residing at Lynn, county of Essex, State of Massachusetts, have invented certain new and useful Improvements in Internal-Combustion Engines, of which the following is a specification.

The present invention relates to internal combustion engines of the type utilizing a relatively heavy oil and in which the temperature of the fluid within the cylinder due to compression, is utilized to ignite the charge, and has for its object to improve their construction, particular reference being made to the arrangement of working and pump pistons and cylinders, to the means for scavenging the cylinders, to the arrangement for admitting fuel and compressed air to the cylinders, and to the elimination of puppet and similar valves.

In the accompanying drawing which illustrates one of the embodiments of my invention, Figure 1 is a view partly in section and partly in side elevation of a multi-cylinder engine; Fig. 2 is a sectional view of the same at right angles to Fig. 1; and Fig. 3 is a plan view partly in section on the line 3—3 of Fig. 1.

1 indicates the base of the engine which is provided with side portions that inclose and support the crank-shaft 2. To the top of the base are secured a number of working cylinders 3 arranged in pairs, two of such pairs being illustrated, and also a number of pump cylinders 4 axially aligned with the working cylinders.

Each pump cylinder is much larger in diameter than the working cylinder so as to insure a supply of fresh air largely in excess of that displaced by the working piston. I find it desirable in some cases to make the pump cylinders fifty per cent larger than the working cylinders. This

figure is given as an illustration and not as a limitation of my invention. In each cylinder is located a close fitting piston, the working piston 6 and the pump piston 7 being connected by a rod 8. The pistons for each pump and working cylinder are cast in one unit, and the pump piston in addition to operating as such serves as a guide for the working piston.

The working cylinder 3 is provided with ports 9 that admit a large amount of pure

air for scavenging purposes. It is not, however, provided with exhaust ports for the burned products of combustion as will appear later.

The pump cylinder 4 is provided with air admitting ports 10 located in the cylinder near the upper end of the piston stroke and controlled by the piston 7. The lower end of the cylinder has an outlet 11 that discharges into the receiver 12. This receiver is common to the pump cylinders 4 and 13, air from the latter being conveyed to it by the conduit 14. In other words, the two pumps supply air in multiple to the receiver and to the working cylinder 3. This receiver must have, for the best operation, a capacity substantially equal to the displacement of both pump pistons to avoid losses due to compression. The receiver 12 is connected to an annular chamber 15 that surrounds the cylinder 3 and from which the air ports 9 enter the cylinder proper and are controlled by the piston 6.

The working cylinder 17 that is paired with working cylinder 3 is provided with exhaust ports 18 that discharge into a cylindrical chamber 19, the latter communicating with the exhaust pipe. The exhaust ports are controlled by the working piston 21. These ports are common to both working cylinders, said cylinders being connected at the top by a conduit 22. Fuel in the nature of a rather heavy oil is forced into the conduit 22 by air under a pressure which materially exceeds that caused by the compression of the working pistons. For example the working pistons may compress the pure air in the cylinders after the burned products of combustion have been forced out to a pressure of 500 lbs. per square inch. On the other hand the oil and air may be forced into the conduit 22 and into the working cylinders under a pressure of say 1000 lbs. per square inch.

The pistons are connected by a wrist pin 100 which in turn is connected by the connecting rod 24 to the main crank shaft 2. From this construction it follows that the movements of the pistons are simultaneous. It should further be noted that the pistons 105 for the working and pump cylinders are so arranged that as one piston moves toward its closed end, the other piston moves toward its open end; or in other words, as one piston compresses or expels the contents of its 110

cylinder the other piston is drawing air or gas into its cylinder. It is on account of this latter arrangement that the receiver 12 is provided.

5 Inasmuch as the two working cylinders are connected by the conduit or passage 22 to which the fuel is admitted, it follows that they receive combustible simultaneously and are in multiple relation as to the reception 10 of combustible and compressed air. On the other hand the burned products of combustion pass serially through the cylinders and the conduit 22 to the single set of exhaust ports 18. Since the ports 15 admitting pure 15 air for scavenging purposes are associated with the cylinder having no exhaust ports it follows that the pure air from the pumps must also pass serially through the cylinders and conduit 22 to the exhaust ports 18. It is 20 further to be noted that the two pumps discharge in multiple into said air ports. Owing to the arrangement of the parts above described and to the fact that the displacement of the pump pistons is greatly in excess 25 of that of the working pistons, the pure air as it rushes through the ports, cylinders and connecting conduit drives before it all of the burned products of combustion and leaves only pure air to be compressed on the 30 inward stroke. Unless the displacement of the pumps is greater than that of the working pistons the cylinders will not be fully scavenged and one of the material features of advantage of my engine will be lost.

35 Driven by the crank shaft or other suitable source of power is a two-stage air compressor 25 of the reciprocating type. Air is compressed therein to whatever pressure it is desired to use in forcing air and fuel 40 (usually a relatively heavy oil) into the working cylinders. The compressor discharges into a receiver 26 through a check valve 27 located in the pipe 28. Air from the receiver is conveyed to the inlet valve 29 by the pipe 30.

35 indicates an upright shaft that is driven from the crank shaft by spiral gears 36. On this shaft is a speed governor 37, the weights of which move the sliding collar 38 up and down. To the collar is connected a lever 39 that raises and lowers the sliding block 40 to change the effective stroke of the fuel pumps. On the shaft 35 is also an eccentric 41 or other means for oscillating 55 the lever 42.

43 indicates a bell-crank lever actuated by the lever 42 and block 40 for reciprocating the plungers of the fuel pump 44. The plungers are forced in one direction by 60 springs and in the opposite direction by the lever. Each plunger serves one pair of working cylinders.

45 indicates a horizontal shaft driven by gearing from the shaft 35. It is employed 65 to open the valves 29 that admit fuel and air

under pressure to the conduit 22 and the working cylinders. On the shaft 45 are cams 46 that engage the rollers on the bell crank levers 47, one such lever being provided for each two working cylinders. The 70 right end of this lever engages the stem of the valve 29, Fig. 1, and raises it against the pressure of the air from the reservoir 26. This valve only remains open for a very short time. For example it may open when the crank is three degrees in advance of its dead center and close after it has moved seven degrees. Owing to the high compression used in my engine, as is the case with this type of engine generally, the fuel starts 75 to burn just as soon as it passes the admission valve 29; thereby obviating the necessity of special sparking or ignition devices.

I have described only one pair of working and pump cylinders and their pistons since 80 the other pairs are similar in construction. The pistons of the several pairs are of course connected to the crank shaft in a manner to balance the thrusts as far as possible.

I may use any suitable form of water 90 jacketing for cooling the cylinders.

By arranging the ports as described and using the pistons as valves I avoid the use of puppet and other valves which are a great source of trouble and which are difficult to 95 keep tight. Another and important feature is that my arrangement permits of operating the engine at any desired high speed and the ports will always be opened and closed at the proper times. By using one set of exhaust ports for two working cylinders I avoid complications and also insure the complete scavenging of the cylinders with an excess of pure air over that necessary to fill the cylinder spaces. This latter feature is a 100 most important one as it directly affects the economy of operation.

In accordance with the provisions of the patent statutes, I have described the principle of operation of my invention together 110 with the apparatus which I now consider to represent the best embodiment thereof; but I desire to have it understood that the apparatus shown is only illustrative, and that the invention can be carried out by other 115 means.

What I claim as new and desire to secure by Letters Patent of the United States, is:—

1. In an engine of the character described, the combination of a pair of working cylinders, pistons that compress air in one end of said cylinders to a temperature above the igniting temperature of the fuel, a crank shaft connected with the pistons, a conduit connecting the cylinders at their compression ends, exhaust ports for one of the working cylinders, a pair of air pumps, the pistons of which have greater displacement than the working pistons, means for conveying the air from both pumps to the other 125 130

working cylinder, said air flowing through the cylinders and their connecting conduit serially and driving out the burned products of combustion, and a means including air under pressure for injecting fuel into the conduit connecting the cylinders wherein it is ignited by the high temperature air compressed by the working pistons.

2. In an engine of the character described, 10 the combination of a pair of working cylinders and their pistons, a crank shaft connected to the pistons, a conduit connecting the cylinders, exhaust ports for one of said cylinders only which are controlled by the 15 working piston therein, air-admitting ports for the other working cylinder which are controlled by the piston therein, a fresh air pump whose piston displacement is materially greater than that of the working pistons, a conduit conveying air from the pump to the said air ports, the air from said ports flowing serially through the cylinders and conduit and escaping through the exhaust ports, a fuel supply, and an air compressor 20 for forcing fuel and air into the cylinder spaces of both of the working cylinders against the compression produced by the working pistons.
3. In an engine of the character described, 25 30 the combination of a pair of working cylinders, pistons in the cylinders that compress air in the ends thereof, a crank shaft connected to the pistons, a conduit connecting the compression spaces of the cylinders, an 35 air pump having a piston displacement

greater than that of the working pistons, a receiver connected thereto having a cubical capacity substantially equal to the displacement of the pump, air-admitting ports in one of said cylinders that communicate with the receiver and are controlled by the piston, exhaust ports in the other cylinder which are controlled by its piston, and means including air under pressure for injecting fuel into said conduit where it is ignited by the high temperature air forced into it from both working cylinders.

4. In an engine of the character described, the combination of a pair of working cylinders and their pistons, a crank shaft for the pistons, a conduit connecting the cylinders at their compression ends, an air pump having a piston displacement greater than that of the working pistons, a receiver connected thereto, air-admitting ports in one of said cylinders that communicate with the receiver and are controlled by a working piston, exhaust ports in the other cylinder which are controlled by its piston, a staged air compressor, and a receiver that receives air from the compressor and forces fuel into the conduit where it is ignited by the high temperature air forced into it from the cylinders by the working pistons.

In witness whereof, I have hereunto set my hand this 22d day of June, 1911.

HERMANN LEMP.
